UNITED STATES PATENT OFFICE.

DAVID M. TULLOCH, OF NEW YORK, N. Y., ASSIGNOR OF ONE-HALF TO ERIC T. CHRISTENSEN, OF BROOKLYN, NEW YORK.

EXPLOSIVE-ENGINE.

1,086,245.

Specification of Letters Patent.

Patented Feb. 3, 1914.

Application filed May 31, 1912. Serial No. 700,636.

To all whom it may concern:

Be it known that I, DAVID M. TULLOCH, a citizen of the United States, and a resident of the city of New York, borough of Brooklyn, in the county of Kings and State of New York, have invented a new and Improved Explosive-Engine, of which the following is a full, clear, and exact description.

My invention relates generally to explosive engines and, more particularly, it is directed to an engine of this type having an improved means of control of intake and exhaust.

The principal design of the present invention is to provide a new and improved valve mechanism for controlling the intake and exhaust of cylinder gases, the said mechanism being positively actuated by the reciprocating piston.

A further design of the invention is to provide an engine which, as an entirety, and especially in the construction and operation of the valve mechanism, will present a construction doing away with the use of separately driven cams or separately actuated valve rods, the mechanism being controlled directly by the piston.

Advantages of the invention, following from the preferred form of the engine illustrated, will appear as the description thereof proceeds, the features of construction, producing new and useful results, being comprehended within the spirit and scope of the claims.

Reference is to be had to the accompanying drawings, forming part of this specification, in which similar characters of reference denote corresponding parts in all the views, and in which—

Figure 1 is a side view of a four-cylinder engine embodying my invention; Fig. 2 is a vertical sectional view thereof; Fig. 3 is a horizontal sectional view on the line 3—3 of Fig. 2; while Fig. 4 is a perspective view of one of the valves.

In setting forth the construction and operation of the engine, one cylinder will be chosen, it being obvious, however, that any desirable and suitable number of cylinders and pistons with their valve mechanisms may be embodied in a unitary structure, as shown in Fig. 1, in order to provide a balanced engine and one of greater power.

The cylinder 1 is preferably inclosed with in a suitable casing 2, the space 3 between

the cylinder and casing being designed to carry a suitable cooling medium, the cylinder and the casing being formed of a single casting if so desired.

Reciprocating within the cylinder is a piston 4 of extended length, whereby the cylindrical bearing portion 5 results, the piston being provided with a transversely extending pin 6 on which the pitman 7 is mounted, the other end of the pitman being in pivotal engagement with a crank pin, or rod, or disk 8. The particular size of the piston and the cylinder will depend primarily upon good design, while the material and length of the pitman may be varied, depending on such factors, the outer end of the pitman being connected with the crank pin, or rod by any suitable form of box receiving the pin or rod.

The head of the cylinder is provided with a suitable threaded opening into which the ordinary type of spark plug 9 is entered, the spark plug forming a terminal for a lead 10 from a suitable and convenient source of current. Adjacent the head end of the cylinder and preferably at diametrically opposite points are ports 11, 11^a, which ports are designed to permit the intake and exhaust of gases; intermediate the open end of the cylinder and the said ports and preferably at diametrically opposite sides are the longitudinally extending slots or recesses 12, 12^a, the said piston 4 being provided with projections extending at a normal angle, such as pins 13, 13^a, these pins reciprocating within the slots or recesses as the piston moves back and forth within the cylinder.

Referring particularly to Fig. 3, it will be noted that at opposite sides of the cylinder and preferably integral therewith are smaller structures 14, 14^a, which structures are preferably of circular conformation, being tubular in their nature, which structures receive and contain the intake and exhaust valves 15, 15^a, the particular form of each of which is substantially the same and shown in Fig. 4.

Referring particularly, then, to Fig. 4, it will be noted that this valve is substantially cylindrical in shape, and adjacent one end is provided with an opening 16, the central portion of the valve adjacent this end being recessed, as at 17, the said opening and recess being communicating; on the outside 110

of this valve and extending around the whole extent thereof is a zig-zag groove 18 forming a continuous path, in that the groove is closed on itself, the particular utility of the groove being apparent from Fig. 3 of the drawings wherein it is shown that the said laterally extending projections 13, 13^a, at opposite sides of the piston always engage in these grooves. Continuing, with reference to Figs. 2 and 3, these cylindrical valves are positioned within the circular structures 14, 14^a, which form, in effect, valve containers, being closely fitted therein, the upper open ends of the valves 15 communicating with openings 19, 19^a, in the removable heads of these containers or structures 14, 14^a, which heads receive the tubes 20, 20^a, forming intake and exhaust tubes respectively. In order to conveniently and efficiently mount the valves in these containers and to make the constant rotation of the valves during operation of the engine as frictionless as possible, and in order to increase the efficiency of the engine, the top 25 and bottom of the valve structure are preferably provided with raceways 21 designed to receive steel balls 22, whereby a rolling contact is provided.

The particular relation of the openings 30 16 in the valves of any one cylinder will, of course, be determined with reference to the position of the piston within the cylinder, the valves provided with these openings being so timed as to permit the openings 35 to come into register with the ports 11, 11^a, in the cylinder so that admission, compression, explosion, and exhaust are taken care of at proper intervals. As the engine operates, the reciprocation of the piston 40 keeps the cylindrical valves 15, 15^a, in constant rotation, whereby the supply of the explosive mixture is provided, as well as the disposal of the exploded mixture, turning of these valves being constant.

45 The valves are positively actuated by the piston, that is, considering the projections or lateral extensions 13, 13^a, as parts of the piston, the piston then directly engages and directly actuates the valves without the intervention of any intermediate elements. This reduction of the number of moving parts reduces the energy consumed by the engine itself, thereby providing for a greater proportion of the energy developed for useful work. The particular formation of the zig-zag groove and the length of such groove will, of course, depend on characteristics of the piston, such as the stroke, as well as on the size of the valves, the idea being always embodied, which is, that intermittent registration of the opening 16 in the valves with the ports of the cylinder provides for the intake of explosive mixtures and for the disposal thereof at proper intervals.

55 60 Referring particularly to Figs. 1 and 2,

wherein is set forth a particular embodiment of a four-cylinder engine, it will be noted that the structure conveniently lends itself for production of the cylinders and the valve-inclosing structures in a single 70 part, that is, of integral construction, whereby the work and labor of assembling the engine is materially reduced, all of the parts, by reason of such construction being so tied together that efficient operation 75 is promoted. In order to provide for lubrication of the valves and the cylinders, this integral casting at proper places may be provided with oil or grease cups 23, or any desirable or convenient system of lubrication 80 may be employed. The integral structure embodying the cylinders and valve-containing structures may be conveniently supported on two standards, one of which 85 is shown in Fig. 1, the standard being 90 carried on any desirable support and held thereto in any convenient manner. These standards also provide the necessary bearings 25 for the main driving shaft 26 which embodies the crank pin, or rod, or disk. 95

From a consideration of the structure shown in the drawings, it is obvious that many desirable results follow the use of the engine set forth; the moving parts are all inclosed, which is of advantage in maintaining cleanliness, which promotes efficiency of operation; the moving parts of the engine are reduced, due to the omission of the intermediate valve-actuating mechanism, which tends to noiselessness; finally, 100 the engine as an entirety presents a structure which, in a commercial sense, is desirable in that one of given power may be produced at less cost than another engine of the same power but made up of many more 105 moving elements.

Having thus described my invention, I claim as new, and desire to secure by Letters Patent:—

1. The combination of a power cylinder 110 having a piston reciprocating therein, with a plurality of valves for controlling the intake and exhaust gases, the valves embodying cam grooves, together with means actuated by the piston and engaging the 115 grooves, whereby the reciprocating movement of the piston imparts a turning movement to the valves.

2. An explosive engine comprising a cylinder having recesses in its side walls, with a plurality of revolvable valves for controlling the intake and exhaust of gases, pins carried by the piston entering the recesses and engaging the valves, whereby the reciprocating piston imparts a constantly turning movement to the valves during operation of the mechanism.

3. An explosive engine comprising a power cylinder having recesses therein, the piston of the cylinder being provided with 130

- laterally extending pins entering the recesses, valves for controlling the intake and exhaust of gases, the said valves being provided with zig-zag grooves engaging the 5 said pins, whereby a reciprocating movement of the piston imparts a constantly turning movement to the said valves.
4. An explosive engine embodying a power cylinder with a reciprocating piston 10 therein, a power element driven by the piston, and a revoluble valve element to one side of the cylinder for controlling the admission of gas thereto, and operatively connected with the piston independently of 15 said driven element; the movement of the piston imparting a turning movement to the said valve element.
5. An explosive engine comprising a power cylinder having a reciprocating piston 20 therein, a power element driven by the piston, the cylinder being provided with ports, a plurality of independent revoluble valves having openings therein adapted to register at determined intervals with the 25 said ports, the said valves being in communication with a source of supply and a medium to receive the exhaust, and means independent of said power element engaging the piston and also engaging the said valves, whereby the movement of the piston imparts independent movements to the said valves.
6. An explosive engine comprising a power cylinder, the piston of the cylinder being provided with laterally extending pins, valves for controlling the intake and exhaust of gases, the valves being provided with zig-zag grooves in which the said pins engage, whereby the reciprocation of the 30 piston imparts a turning movement to the said valves.
7. An explosive engine comprising a cylinder having recesses in its side walls, a plurality of revoluble valves for controlling the intake and exhaust of gases, and means 35 carried by the piston entering the recesses and engaging the valves, whereby the reciprocation of the piston imparts a turning movement to each of the valves during operation of the engine.
8. The combination of a power cylinder having a piston reciprocating therein, a plurality of valves for controlling the intake and exhaust gases, each of the valves being provided with a cam groove, the said cylinder being provided with recesses, and pins carried by the piston passing through the recesses and engaging the said grooves, whereby the back-and-forth movement of the piston imparts a turning movement to 40 the valves.
9. An explosive engine, embodying a power cylinder having a piston thereon, a power element driven by the piston, and a valve commanding communication with the cylinder and controlling the admission of the charge thereto, the said valve being operatively connected with the piston independently of the said driven element, to actuate 45 said valve.
- In testimony whereof I have signed my name to this specification in the presence of two subscribing witnesses.
